J. H. LOPER

ELECTRIC HEATER FOR CRANK CASES

Filed March 27, 1925

FIG. 1

FIG. 2.

Inventor

J. H. LOPER,

By Jerry A. Mathews

FIG. 3.

Attorney

UNITED STATES PATENT OFFICE.

JAY H. LOPER, OF LINCOLN, NEBRASKA.

ELECTRIC HEATER FOR CRANK CASES.

Application filed March 27, 1925. Serial No. 18,814.

My invention relates to improvements in an electrical heating device, for heating the oil in the crank case of the internal combustion engine, in an automobile.

The important objects of the invention are to provide for the correct amount of resistance; the proper heating of the oil, with the small consumption of current; and to provide a device of the above mentioned character which may be used with a 6 or 12 volt battery.

Other objects and advantages of the invention will be apparent during the course of the following description.

In the accompanying drawings forming a part of this specification and in which like numerals are employed to designate like parts throughout the same.

Figure 1 is a side elevation of the heater, Figure 2 is a central longitudinal section through the same, and,

Figure 3 is a transverse section taken on line 3—3 of Figure 2.

In the drawings, wherein for the purpose of illustration is shown a preferred embodiment of my invention, the numeral 5 designates the crank case of an internal combustion engine. I drill a hole 6 through the crank case 5, preferably below the oil level.

The heater embodies a preferably cylindrical tubular body portion 7, formed of metal, such as iron or any other suitable material. One end of this tubular body portion is screw-threaded, as shown at 8, for engagement with a contact-cap 9, preferably formed of brass. The opposite end of the tubular body portion 7 is also screw-threaded for engagement with a reducer or coupling 10, having its outer end internally screw-threaded for receiving a bushing 11. The tubular body portion 7 passes through the opening 6 and a flange 12 engages the inner wall of the crank case, while the reducer or coupling 10 engages the outer wall. The tubular body portion 7 is grounded to the crank case, as is obvious.

The bushing 11 may be adjusted longitudinally with respect to the reducer or coupling 10, by turning the bushing therein, and this bushing carries a tubular insulator 13,

having a shoulder 14, engaging the inner end of the bushing 11, as shown. This insulating sleeve is preferably formed of porcelain, and receives a contact element 15, passing therethrough. This contact element is preferably formed of brass. The contact element 15 is provided at its inner end with a head 16, while its outer end is screw-threaded, for engagement with a nut 17, by means of which the contact element may be clamped to the insulating sleeve.

The head 16 is provided with a conical or beveled recess 18, for receiving the conical or beveled end 19, of a resistance element 20, formed of carbon. The opposite end 21 of this resistance element 20 is conical or beveled, and fits within a conical or beveled recess 22, formed in the contact-cap 9.

An important feature of the invention is the use of the carbon resistance element 20, with the conical or beveled ends, engaging within the conical or beveled recesses of the contact elements 15 and 9. This permits of the proper regulation of the current, and the proper regulation of the resistance.

In operation, the element 15 has electrical connection with one side of a source of current, the opposite side of which is grounded to the crank case 5. It is thus seen that when the circuit is closed, the current will pass through the resistance element 20.

It is to be understood that the form of my invention herewith shown and described is to be taken as a preferred example of the same, and that various changes in the shape, size, and arrangement of parts may be resorted to without departing from the spirit of my invention or the scope of the subjoined claim.

Having thus described my invention, what I claim is:

An electrical heater comprising a tubular body portion having its opposite ends threaded, said tubular body portion being provided with a flange near one threaded end, a contact cap engaging one threaded end of the tubular body portion and having electrical contact therewith and provided with a conical recess, a tubular coupling engaging the opposite threaded end of the tubular body portion and adapted to clamp

the same to a support arranged between it and said flange, a bushing having screw-threaded engagement within the outer end of the coupling and longitudinally adjustable therein, a tubular insulator carried within the bushing, a contact element arranged within the tubular insulator and having a conical recess, and a carbon resistance element extending longitudinally within the tubular body portion and having conical ends engaging within the conical recess. In testimony whereof I affix my signature.

JAY H. LOPER.
